UNITED STATES PATENT OFFICE.

ORVAL B. FOSTER AND LESTER FOSTER, OF FORT SMITH, ARKANSAS.

RADIATOR COMPOSITION.

1,407,995.

Specification of Letters Patent. Patented Feb. 28, 1922.

No Drawing.

Application filed July 8, 1920. Serial No. 394,737.

To all whom it may concern:

Be it known that we, ORVAL B. FOSTER and LESTER FOSTER, citizens of the United States, residing at Fort Smith, in the county of Sebastian, State of Arkansas, have invented a new and useful Radiator Composition; and we do hereby declare the following to be a full, clear, and exact description of the invention, such as will enable others skilled in 10 the art to which it appertains to make and use the same.

The invention relates to radiator anti-leak composition, particularly adapted for placing in radiators used in connection with 15 internal combustion engines of motor driven vehicles, and has for its object to provide a compound of this character, which when placed in the radiator, will pass through the same and will adhere to the walls thereof 20 where it will solidify and stop leaks in the radiator, thereby obviating the necessity of soldering the leaks in radiators.

A further object is to provide a radiator composition, which composition may be easily and quickly placed in the radiator and 25 leaks therein securely sealed.

A further object is to provide a radiator composition consisting of a mixture of paper pulp, corn starch, wood alcohol and hydro- 30 chloric acid.

It has been found that by mixing paper pulp, corn starch, wood alcohol and hydrochloric acid that a radiator composition is provided, which composition will rapidly dry and adhere to the walls of the radiator 35 in such a manner as to stop leaks therein.

To obtain the best result it has been found that the following proportions of ingredients should be used.

60 parts of paper pulp.	40
35 parts corn starch.	
4 parts of wood alcohol.	
1 part of hydrochloric acid.	

To the above ingredients may be added coloring matter as desired, however, it is to 45 be understood that the coloring matter may be eliminated or used as desired.

The invention having been set forth what is claimed as new and useful is:—

A radiator compound comprising a mixture of fibrous pulp, corn starch, wood alcohol, hydrochloric acid and coloring matter.

In testimony whereof we have signed our names to this specification in the presence of two subscribing witnesses.

ORVAL B. FOSTER.
LESTER FOSTER.

Witnesses:

J. C. HUMPHREY,
THELMA SELF.
